UNITED STATES PATENT OFFICE.

JAMES H. HARPHAM, OF LINCOLN, NEBRASKA.

GOLF BAG.

Application filed June 12, 1922. Serial No. 567,803.

To all whom it may concern:

Be it known that I, JAMES H. HARPHAM, a citizen of the United States, residing at Lincoln, in the county of Lancaster and 5 State of Nebraska, have invented certain new and useful Improvements in Golf Bags, of which the following is a specification.

This invention relates to improvements in golf bags.

10 The ordinary golf bag comprises a cylindrical body which is provided with a bottom held in place in a more or less insecure manner and usually not protected against wear. As a consequence if the bag is dragged over 15 the ground, which is usually done through carelessness, the bottom soon becomes mutilated and the bag is rendered unfit for use long before the body thereof has become appreciably worn. Therefore, it is one of the 20 primary objects of the present invention to provide a novel construction and arrangement of the bottom of such a bag and also means for protecting the same from wear so that even should the bag be carelessly 25 dragged over the ground the bottom thereof will remain intact, in all probability until the body of the bag has become worn to such an extent as to substantially render the entire bag unfit for further use.

30 Also in the ordinary construction of golf bags stay rods are arranged within the walls of the bag to stiffen and strengthen the walls, but the ends of said rods are ordinarily left free or, in other words, are not 35 secured or anchored to the wall and as a consequence they soon work through the bottom of the bag thereby necessitating repairs. It is therefore a further object of the present invention to provide for the anchorage 40 of the ends of the stay rods in such a manner as to insure against the displacement of the rods and prevent them working through the ends of the bag.

In the accompanying drawings:

45 Figure 1 is a perspective view of a golf bag constructed in accordance with the present invention;

50 Fig. 2 is a sectional perspective view in detail illustrating the construction of the bag;

55 Fig. 3 is a detail horizontal sectional view through the bag taken substantially on the line 3—3 of Fig. 2 looking in a downward direction;

Fig. 4 is a perspective view of one of the stays;

Fig. 5 is a perspective view of the protecting rim for the bottom of the bag;

Fig. 6 is a view similar to Fig. 2 illustrating a modified form of the invention; 60

Fig. 7 is a fragmentary perspective view illustrating a modification of the stay.

The bag embodying the invention comprises a body which is indicated in general by the numeral 1 and which is of the usual cylindrical form, the wall of the body being indicated by the numeral 2 and the bottom thereof by the numeral 3. In the preferred form of the invention illustrated in the drawings the wall 2 is preferably formed 65

from leather, a sheet of this material being rolled to the required form and its edges being overlapped and united by a lacing 4 extending longitudinally of the wall. The wall is preferably provided, in this form 70

of the invention, with a lining 5 of canvas, duck, or any other material suitable for the purpose, and the upper edge portion 75

of the sheet of leather comprising the wall 2 is overturned in an inward direction to 80

form a hem 6 embracing and securing the upper edge of the lining 5, the hem being permanently established preferably by a line of stitching 7 extending circumferentially of the upper end of the wall. The 85

hem thus formed encloses a reinforcing and anchoring band 8 which is of metal and annular in shape and preferably formed from a strip of metal, the upper and lower 90

edge portions of which are overturned upon themselves as indicated by the numeral 9 so as to reinforce the band. While this band 95

serves as a means for retaining the upper end of the body of the bag in proper shape, it performs another function, which will 100

presently be pointed out. The lower end of the body of the bag is reinforced by a number of sections 11 in the form of pieces 105

of leather arranged in an annular series about the inner surface of the wall 2, their lower edges being in registration with the 110

lower edge of said wall, and their upper edges being preferably skived, as indicated by the numeral 12, so as to prevent them

being torn loose when the golf sticks are inserted into the bag. These reinforcing 115

pieces 11 are united along their upper skived edges to the wall 2 of the bag by lines of stitching 13, and at their lower edges by lines of stitching 14. The relatively adja-

cent perpendicular edges of the reinforcing pieces 11 are likewise preferably skived

as indicated by the numeral 15 and are united to the wall 2 by lines of stitching 16, which lines of stitching also secure the longitudinal edges of strips 17 of leather or other suitable material, which strips between their secured longitudinal or vertical edges are disconnected from the wall of the body and form stay pockets extending longitudinally of the inner surface of the body. At 10 their lower ends the strips span the spaces between the edges 15 of the reinforcing pieces 11 so as to provide well defined pockets 18 for the lower ends of the stays. Before proceeding to a description of the 15 stays, the construction and arrangement of the bottom will be pointed out. The bottom 3 is preferably formed from a circular blank of stiff leather as, for example, sole leather and its peripheral portion is overturned in 20 a downward direction as indicated by the numeral 19. The said bottom is snugly fitted into the lower end of the body 2 of the bag and is united to the wall of said body by the line of stitching 14 heretofore referred to, this stitching passing through 25 the overturned peripheral portion 19 of the said bottom. By overturning the peripheral portion of the bottom 3 as described, the central or body portion of the bottom 30 is spaced above the lower edge of the wall of the body 2 of the bag so that its undersurface will not come into direct contact with the ground and will thus, to a certain extent, be protected from wear. 35 In order to reinforce the lower end of the bag and protect the lower edges of the wall of the body 2, the reinforcing pieces 11, and the overturned peripheral portion 19 of the bottom 3, from wear when the bag is 40 carelessly dragged over the ground surface, a metallic rim, indicated by the numeral 20, is provided. This rim is best illustrated in Fig. 5 of the drawings, and is, generally speaking, of annular form and comprises 45 inner and outer walls 21 and 22 which are concentric to each other, and a connecting bottom wall 23 preferably rounded at its juncture with the lower edges of the walls 21 and 22. In other words, the rim may 50 be said to consist of an annular channeled body. The rim is fitted to the lower edge portion of the body of the bag which portion comprises the lower edges of the wall 2, reinforcing pieces 11, and overturned peripheral portion 19 of the bottom 3, with 55 this said edge portion seating within the channel of the rim, the wall 21 of the rim extending along the inner surface of the overturned peripheral portion 19 of the bottom 3, and the wall 22 of the rim extending about the outer surface of the wall of the body 2 at the lower edge of said body. Rivets 24 are secured through the walls 21 and 22 of the rim and through the parts 60 received within the channel of the rim and

serve to permanently unite the rim with the body of the bag. At this point it will be understood that the rim constitutes not only a reinforcing and form retaining means for the lower end of the bag, but also serves 70 as a most efficient means for protecting the lower end of the bag from wear when the bag is carelessly dragged over the ground surface.

Stays are employed in stiffening and reinforcing the wall of the body of the bag and these stays are preferably of the form shown in Fig. 4 and are indicated in general by the numeral 25. Each of the stays 25 comprises a rod 26 of a suitable length to the ends of which rod are applied tips 27 preferably clamped thereabout and frictionally held thereon and having flattened terminals 28 provided with openings 29. The rivets 24 which secure the rim 20 to the lower edge of the bag are secured through the openings 29 of the tips at the lower ends of the stays 25, and these stays are housed within the pockets provided by the strips 17. The upper ends of the stays extend between the wall of the body 2 and the overturned portion 6 of said wall, and the flattened portions 28 of the tips at the said upper ends of the stays are disposed against the band 8, and rivets 30 are secured through these parts and thus anchor the upper ends of the stays. By providing the tips 27 at the ends of the rods 26, the stays are not weakened, as would be the case if they were formed as shown in Fig. 7 in which figure the ends of the rod 26 are illustrated as flattened out as at 31 and formed with openings 32 corresponding to the openings 29; however, the stays may be thus formed if desired. 90

The form of the invention shown in Fig. 6 of the drawings is substantially identical with that shown in the other figures, except that in this instance the body of the bag is formed of canvas or duck or some other heavy cloth material. The bag will be provided with the usual carrying strap 33, handle 34, and ball case 35, although these parts do not enter into the present invention. 105

Having thus described the invention, what is claimed as new is:

1. In a golf bag, a body, a bottom disposed within the lower end of the body and having an overturned peripheral portion extending about the inner side of the wall of the body at said end, reinforcing members arranged about the inner surface of the wall of the body at said end and having their adjacent edges relatively spaced, strips secured longitudinally to the inner surface of the body and at their lower ends spanning the spaces between the edges of adjacent reinforcing members to provide pockets, stays seated in said pockets and reinforcing the wall of the body, an annular channeled wear member fitted on to and enclosing the lower end edge 110

portion of the wall of the body, the overturned peripheral portion of the bottom, and the lower edge portions of the reinforcing members, and securing elements secured 5 through the walls of the wear member and through the parts housed within the channel thereof and likewise anchoring the lower ends of the stays.

2. A golf bag comprising a cylindrical 10 body, arcuate reinforcing pieces disposed against the inner surface of the wall of the body at the lower portion thereof, the relatively adjacent vertical edges of the reinforcing pieces being spaced, a bottom within the 15 lower end of the body having an overturned peripheral portion extending circumferentially about the inner side of the said rein-

forcing pieces, an annular channeled wear member fitted to the lower end of the body and the overturned peripheral portion of 20 the bottom and likewise enclosing the lower end portions of the reinforcing pieces, pockets secured to the inner side of the wall of the body and extending vertically longitudinally thereof, the lower portions of the pockets having their opposite sides united to the said spaced vertical edge portions of the reinforcing pieces and to the wall of the body, and reinforcing rods seated within the pockets and extending vertically of the wall of 30 the body.

In testimony whereof I affix my signature.

JAMES H. HARPHAM. [L. S.]
